UNITED STATES PATENT OFFICE.

HOMER E. PIERCE, OF BROOKLYN, NEW YORK.

STEREOSCOPE.

SPECIFICATION forming part of Letters Patent No. 296,055, dated April 1, 1884.

Application filed January 14, 1884. (No model.)

To all whom it may concern:

Be it known that I, HOMER E. PIERCE, of Brooklyn, in the county of Kings and State of New York, have invented a new and useful 5 Improvement in Stereoscopes, of which the following is a full, clear, and exact description, reference being had to the accompanying drawings, forming part of this specification.

My invention relates to that class of stereoscopes that are provided with a handle or standard that is hinged to the base of the instrument, whereby it may be rocked on the handle or base and set at any desired angle therewith; and it consists in the devices herein described and claimed, whereby the instrument may be readily and conveniently locked in any desired position and unlocked and shifted therefrom.

Figure 1 is a side view in outline of a stereoscope, to the base of which is hinged a handle, in the hinge of which is contained my invention. Fig. 2 is an edge view of the parts constituting the hinge, together with detached portions of the handle and base of the instrument in section. Fig. 3 is a side view, partly in section, of detached parts of the said base and handle and hinge; and Fig. 4 is a similar view, showing the opposite side of the same.

A represents a stereoscope. B is a toothed segment made fast on one of its straight edges to the under face of the base *a* of the instrument. Preferably the segment is riveted or otherwise secured to a metal plate, *b*, that is fastened by screws or otherwise to said base. 35 To this segment the handle *C* is hinged by means of jaws or plates *c c'*, that project from the end of the handle, one on either side of the segment. A pin, *d*, passing through the said plates and segment, secures the plates and 40 segment together, and forms the pivot of a hinge on which the segment may swing back and forth between the plates. The hole *f* in the segment through which the said pivotal pin passes is slotted, as shown, so that the 45 handle may be shifted up and down on the segment into the position shown in Figs. 1 and 4, or that shown in Fig. 3. A stop-pin, *e*, passing through both plates *c c'*, is rigidly secured in place, and it is so placed relatively to

the pivotal pin *d* and the teeth of the segment 50 that when the handle and plates *c c'* are pushed upward so that the pivotal pin is at the upper end of the slotted hole *f*, the stop-pin *e* will engage the teeth on the segment, and when they are drawn down so that the 55 pivotal pin is at the lower end of said hole *f*, the said stop-pin will be disengaged from said teeth.

The plates *c c'* may be made to suitably grasp the segment, so that the friction between them 60 shall prevent their undesired movement in the hinge and make it necessary to exert a little force to shift the plates on the segment, as described.

It is evident that the instrument may be set 65 at any desired angle on the handle or on a standard set in a base (which may be used instead of a simple handle) and then locked in position by forcing the segment down into engagement with the described stop-pin, and 70 that the position of the instrument may be altered by disengaging the stop-pin from the segment and swinging it on its hinge.

I do not intend to limit myself to the precise form and construction or position of the stop-pin. Any equivalent stop attached to the handle or hinged plates may be employed. So, 75 also, if preferred, in place of two independent plates inserted in the end of the handle, a single shank, rod, or plate forked at the upper 80 end may be used.

I have described my lock-hinge as applied to a stereoscope; but it is obvious that it may be equally applicable to a graphoscope or any other analogous instrument.

What I claim as my invention, and desire to 85 secure by Letters Patent, is—

The combination, with a stereoscope and its handle or standard *C*, of the described lock-joint formed of the jaws *c c'*, provided with 90 the slot *f* and stop-pin *e*, and the toothed segment *B*, pivoted in the said slot between the said jaws, as and for the purpose described.

HOMER E. PIERCE.
